This technical drawing illustrates a complex mechanical assembly, possibly a valve or pump. The drawing is annotated with a large number of part numbers, including 20, 85, 84, 83, 23, 34, 27, 31, 22, 82, 112, 110, 111, 116, 28, 30, 29, 36, 33, 105, 11, 35, 96, 78, 98, 16, 89, 77, 75, 90, 95, 52, 56, 55, 41, 100, 102, 101, 104, 46, 108, 107, 145, 105, 119, and 114. The assembly features a central vertical shaft, a housing with a flange, and a cover plate with a central hole. Various internal components like springs and seals are indicated by the part numbers.

Gastonia, N. C., a corporation of North
Carolina

Application December 4, 1936, Serial No. 114,191

5 Claims. (Cl. 289—3)

This invention relates to knotters, and particularly to a device for tying a weaver's knot.

It is well known that knotters must be designed, particularly as to details, for the particular characteristics of the thread or strand to be tied. For instance, wool thread requires one type or particular design, fine thread another and the design also varies with materials of which the thread is composed. For example, rayon threads are difficult to tie because of the texture of the thread and because it is slippery and cannot be firmly held.

This invention has for one of its objects to provide a knotter so constructed and arranged as to eliminate slack during the tying of the knot, thus tying a tighter knot.

Another object of the invention is to provide a knotter so constructed and arranged that both ends of the thread, namely, the ends on opposite sides of the knot, will be pulled tight during the tying operation, by the stripper that removes the knot from the tying bill.

Further objects of the invention will appear from the following specification taken in connection with the drawings which form a part of this application, and in which

Fig. 1 is a side elevation of a knotter constructed in accordance with the invention;

Fig. 2 is a similar view of the opposite side of the knotter, parts being omitted for the sake of clearness;

Fig. 3 is a front end elevation of the knotter;

Fig. 4 is a longitudinal sectional elevation illustrating the mechanism for performing the various operations;

Fig. 5 is a view similar to Fig. 2 but showing the parts illustrated in the position taken when the operating lever has been pulled down but has not reached its extreme lower position;

Fig. 6 is a longitudinal sectional elevation showing the frame, operating lever and thread positioning means at one side of the frame in the positions taken before the knotter is operated;

Fig. 7 is a view similar to Fig. 6 but showing the parts in the position taken after a partial operation has been performed;

Fig. 8 is a view similar to Fig. 6 showing further parts of the mechanism in their initial or inoperative positions;

Fig. 9 is a view similar to Fig. 8 but showing the parts in the position taken on the completion of the operation of the knotter;

Fig. 10 is a top plan view of the knotter; and

Figs. 11-16, inclusive, are perspective views on

an enlarged scale showing the different positions of the parts at the various steps in the operation of tying the knot.

The invention briefly described consists of a knotter comprising thread positioning means for crossing the threads at spaced points to form a loop therebetween, a tying bill for forming a knot in the thread, means for cutting the ends of the threads at one side of the knot and means for stripping the knot from the tying bill. The thread engaging and positioning means are so constructed and arranged as to provide a minimum amount of slack and are further so arranged relative to the path of movement of the stripper that the stripper in its operation will exert a pull on the threads at both sides of the knot while the end of one of the threads is still being held by the bill. Thus, both ends of the threads will be pulled tight.

Further details of the invention will appear from the following description.

In the particular embodiment of the invention illustrated, the knotter has a frame comprising a pair of side frames 20 and 21 which are connected and are held in spaced relation by screws 22 and 23 and are also connected and braced by means of other spacing members hereinafter described.

The screw 22 has pivoted thereon the main operating lever 25 having a downwardly extending handle 26 and an upwardly extending arcuate plate 27. Plate 27 has a tail 28 extending upwardly therefrom at the rear end thereof and also has a downwardly extending notch 29 near the front end thereof. Intermediate the notch 29 and the tail 28 the plate has formed along its upper edge an arcuate or cam surface 30.

A spring 31 encircles the screw 22 which forms the pivot for the lever 25. One end of the spring engages a fixed abutment 32 on the side frame 21 and the other end engages a lug 33 which extends laterally from the plate 27 and has formed on the outer end thereof an upwardly extending lug 34.

The side frames 20 and 21 are provided with transverse pin 36 on the outer ends of which are mounted resilient strips or links 37 and 38, which act as tension arms. The strip 37 is pivoted at its front end at 40 to a member 41 which, as shown at 42, is pivoted to the frame member 20.

The front end of the strip or link 37 has a lug 43 formed thereon and the member 41 has a tooth or lug 44 formed thereon.

The front end of the frame member 20 has

secured thereto a bracket 45 having a U-shaped front end 46. The frame member 20 has formed therein a slot 47, the member 20 being offset, as shown at 48, and the link or strip 37 extending through the slot 47 in this offset portion.

The frame members 20 and 21 have formed on the front end thereof upwardly extending horns or lugs 50 and 51. Intermediate the horn 50 and the adjacent portion of the frame member 20 there is positioned an upwardly extending finger 52 which is formed on the bracket 45.

A cross pin 55 connects the horns 50 and 51 and has mounted thereon a U-shaped bracket 56 which has formed thereon a finger 57 which extends upwardly and across the frame of the knoter above the tying bill and is useful in properly positioning the threads to be tied. The bracket 56 is pivoted on the pin 55 and is held in the position shown in Figs. 8 and 9 by means of a spring 58.

The link or strip 38 is provided at its front end with a flange 60, on the upper end of which is formed a hook 61 which engages, positions and guides one of the threads to be tied. The front end of the strip or link 38 is pivoted at 62 to a member 63 which in turn is pivoted at 64 to the frame member 21. The member 63 has an upwardly extending finger 65 formed thereon and also has an upwardly extending lug 66 at the front end thereof, as shown particularly in Fig. 2.

The strip or link 38 has also formed in the upper edge of the flange 60 a notch 67. During the operation of the knoter one of the threads is guided under the hook 61 and through the notch 67, as clearly shown in Figs. 12 and 14.

At the base of the lug 66 on the member 63 there is formed a notch 68 and at the base of the finger 65 there is formed a notch 69, these notches forming pockets for holding and retaining the threads during the movement of the members 38 and 63.

The tying bill is carried by a shaft 75 which is rotatably mounted in one wall 76 of a U-shaped bracket 77 which is secured between the frame members 20 and 21 by means of a bolt or screw 78. The bracket has oppositely extending lugs 79 and 80 which seat in slots 81 formed in the side frame members 20 and 21.

The shaft 75 has connected thereto and extending rearwardly therefrom a spiral screw 82, the rear end of this screw having a pin 83 which seats in an adjustable screw 84 thereon into the wall 85 of the knoter.

The lug 34 which extends upwardly from the plate 27 of the lever 25 engages one surface of the flat spiral strip or screw 82, as shown particularly in Fig. 10, and as the lever 25 is oscillated to operate the knoter by depressing the handle 26 the engagement of the lug 34 with the surface of the flat spiral strip or screw 82 will cause this strip and the shaft 75 to rotate, thus rotating the bill and tying the knot.

The tying bill comprises a stationary member 86, a movable blade 87 and a cutting bill spring 88. The spring 88 extends rearwardly through a slot in a collar 89 which forms the journal for the shaft 75 and through a collar 90 which is carried by the shaft and abuts against the rear surface of the wall 76. The spring 88 holds the cutting bill blade or shearing jaw 87 in shearing engagement with the stationary blade or tying bill 86.

The blade 87 is pivoted to the stationary bill 86 at 95 and has a fan shaped rear end 96 which

coacts with the edge of an opening 97 in the front wall 98 of the bracket 77 to oscillate the blade 87 during the cycle of operation of the tying bill so as to cut one of the threads after the knot has been tied. The tying bill shaft and parts carried thereby are disposed eccentrically in the opening 97 so that the clamping and shearing jaw or blade 87 will be opened when the bill is rotated through an angle of 180° and will remain open until one of the threads is disposed therebetween in the position taken after the bill has rotated approximately 270°. The thread is shown in Fig. 13 as disposed in the open jaws of the bill. When the bill has completed its rotation of 360° or, in other words, again reaches the vertical upstanding position, the shearing blade and clamping jaw will have been closed, thus severing the thread clamped therein. This thread, however, is clamped in the jaws until the stripper, herein-after described, has been moved upwardly to strip the knot from the clamping jaws, the stripper during this operation pulling the knot tight in a manner hereinafter described.

The foregoing description explains how one of the threads is cut by the shearing blade of the tying bill. The other thread is cut by means of shears comprising a stationary blade 100 formed on the bracket 45 and a pivoted blade 101 which is pivoted at 102 to the bracket 45. The pivoted blade 101 is operated by a lever 105 which is pivoted intermediate its ends on the pin 78 and has a fork 106 formed in the rear end thereof. The front end of the lever has formed therein a slot 107 which receives a pin 108 carried by the pivoted shear blade 101.

The lever 105 is operated by a pin 109 which is carried by and projects laterally from the plate 27. This pin, as shown in Fig. 4, is disposed beneath the upper arm of the fork 106 and moves downwardly during the operation of the lever 25 until it engages the lower arm of the fork whereupon the fork is oscillated in an anti-clockwise direction viewing Fig. 4, and raises the pivoted shear blade 101 until this blade coacts with the stationary blade 100 to sever the thread. Fig. 9 illustrates the parts in the position taken after the lever 25 has been depressed to its extreme lower position and the thread has been severed.

After both threads have been severed in the manner above described the stripper is operated to strip the knot from the tying bill and to pull the knot tight during the stripping operation.

The stripper consists of a lever having a U-shaped bracket 110 intermediate the ends thereof which is mounted on a pin 111 extending between the side frame members 20 and 21. On one side of the pivot the lever extends rearwardly in the form of a tail 112 and on the other side of the pivot the lever extends downwardly around or over the bracket 77 and the front end is curved to form an arc extending around and beneath the tying bill and tying bill shaft or shank. The extreme forward end of the stripper is forked, as shown at 113, to form two upwardly extending tines 114 and 115. The fork, as shown particularly in Fig. 3, is disposed above the lowermost portion of the bend or arc of the lever. Furthermore, as shown in Fig. 10, it will be noted that the stripping fork is disposed substantially in alignment with the hook 61 formed on the front end of the tension arm or link 38.

The stripper is operated at the proper point in the cycle of operation of the machine by the tail 28 of the lever 25 which engages a downwardly extending lug or dog 116 formed on the lever.

Fig. 9 illustrates the engagement between these parts and shows the lever in its elevated position after the handle 26 has been depressed to its extreme lower position.

5

Operation

In order to tie two threads together the threads are placed in substantially parallel position across the two front ends of the knoter frame, 10 as shown in Fig. 11. In Figs. 11-16, inclusive, one of the threads A is shaded, the other thread B being shown by two lines in the usual manner. This is done in order that the successive positions 15 of the threads may be more clearly illustrated.

From the showing in Fig. 11 it will be noted 20 that the thread A extends over the shank of the tying bill and is disposed in the rear of the fingers 65 and 52. Furthermore, the thread A is disposed in the notch 69 at the base of the finger 65.

The thread B extends across the knoter in 25 front of the tying bill and is disposed in front of the fingers 65 and 52.

As the handle 26 is depressed rotating the lever 25 in a clockwise direction viewing Figs. 6-9, inclusive, the tension arms or links 37 and 38 will be moved forwardly through the slots 47 in the side frame members 20 and 21. As these members move forwardly the members 41 and 63 will be oscillated on their pivots and will move rearwardly. This will cause the outer ends of the 30 thread A to move forwardly beneath the rearwardly moving ends of the thread B, forming a loop between the crossed ends of the thread, as shown in Fig. 12.

The ends of the thread A are engaged and 35 guided in their forward movement by the hook 61 and notch 67 on the front end of the tension arm or link 38 and by the lug 43 on the tension arm 37.

The thread B has one end moved rearwardly 40 by the rearward movement of the lug 66 on the member 63, the thread being disposed in the pocket 68 at the base of the lug 66. The other end of the thread B is moved rearwardly by its 45 engagement with the lug 44 carried by the member 41. After the two ends of the threads have been crossed in the manner shown in Fig. 12 the tying bill rotates to the position shown in Fig. 11 from which it will be seen that the bill is about to 50 move downwardly between the tension arm 38 and the crossed ends of the threads. The bill continues to rotate, the two ends of the threads being held frictionally during this rotation between the tension arms 37 and 38 and the pivoted 55 members 41 and 63. When the bill reaches the position shown in Fig. 13 one end of the thread B will be received between the clamping and shearing jaw or blade 87 and the stationary blade 86 and spring 88. At this time the corresponding 60 end of the thread A will be cut by the upward shearing movement of the shearing blade 101.

The tying bill continues to rotate until it has 65 rotated through approximately 360° and is again in upright position. When the bill has reached this position the knot has been tied, but has not been tightened. At this stage in the operation the tail 28 of the lever 25 engages the downwardly extending dog or lug 116 on the stripper and elevates the stripper. As the stripper is elevated 70 the end of the thread B between the tying bill and the tension arm or member 38 will be engaged by the fork 113 of the stripper and will be disposed between the tines 114 and 115 of the 75 fork. Furthermore, the end of the thread A be-

tween the hook 61 and the tying bill will extend over the front arcuate portion of the stripper adjacent the fork, as shown in Fig. 15.

During this time the end of the thread B is still being held between the clamping and shearing jaw 87 and the stationary jaw 86 and spring 88. Thus, as the stripper is elevated the knot will be pulled tight by a pulling action on the two ends of the threads being tied. In this way a tight knot is made. Upon the release of the handle 26 the parts are returned to their initial 10 positions by means of the spring 31.

Particular attention is directed to the fact that the fork on the end of the stripper is disposed substantially in alignment with the hook 61 on 15 the front end of the member 38 and that during its upward movement the fork first engages the thread B between the tines of the fork and next engages the thread A which extends over the front arcuate portion of the stripper adjacent the 20 fork. In this way the knot is pulled tight by pulling on both of the threads as the knot is stripped from the tying bill.

Although one specific embodiment of the invention has been particularly shown and described, it will be understood that the invention is capable of modification, and that changes in the construction and in the arrangement of the various cooperating parts may be made without departing from the spirit or scope of the invention, as expressed in the following claims.

What I claim is:

1. In a knoter of the character described, a tying bill, means for engaging, guiding and positioning the threads for knotting prior to the 35 operation of the bill, means for operating the bill to tie the knot, and a stripper having an upwardly projecting prong spaced from the free end thereof around which the thread ends adjacent the knot pass as the stripper is elevated for pulling the knot tight and stripping the knot from the tying bill.

2. In a knoter of the character described, a tying bill, means for engaging, guiding and positioning the threads for knotting prior to the 45 operation of the bill, means for operating the bill to tie the knot, and a stripper having a forked end movable upwardly to engage the two ends of the threads adjacent the knot, with one thread end positioned on each side of the inner prong of 50 the fork, thereby pulling the knot tight and stripping the knot from the tying bill.

3. In a knoter of the character described, a tying bill for tying a knot in a pair of threads, a stripper having a pair of prongs at the end 55 thereof, an outer prong and an inner prong forming a fork, and means for so guiding and positioning the threads during the operation of the knoter that the stripper during its stripping operation will position one thread over the 60 stripper between the prongs of the fork and the other thread over the stripper on the other side of the inner prong.

4. In a knoter of the character described, a tying bill for tying a knot, said bill having a cutting and clamping jaw adapted to cut one thread and to hold the cut end until after the knot is stripped from the bill, a stripper for stripping the knot from the bill, and holding and positioning means for positioning the thread ends being 70 tied, said stripper having an upwardly extending projection arranged to engage both end portions of the thread leading to the knot on the tying bill and to pull said ends tight over spaced portions of the upper surface of the stripper as the 75

knot is stripped from the bill and while one thread end is held by the bill.

5. In a knotter of the character described, a tying bill, means for guiding and positioning threads for knotting prior to the operation of the tying bill, said means comprising a pair of elements disposed at each side of the knotter, one element of each pair operating to feed one thread end forwardly and the other element of each pair 10 operating to feed the other corresponding thread

end rearwardly in crossed relation to the first thread end, a stripper having the thread engaging end thereof disposed normally below the bill and offset laterally therefrom toward one side of the knotter, the forwardly moving thread engaging and positioning element, at that side of the knotter, having its front end offset toward the bill and disposed approximately in the vertical plane of the end of the stripper. 5

EDGAR LEE RAMSEY.
